(57) **CLAIM**

The ornamental design for the wristband for an electronic device, as shown and described.

DESCRIPTION

FIG. 1 is a plan view of a first side of a long segment of a wristband for an electronic device.

FIG. 2 is an edge view of the long segment of the wristband for an electronic device.

FIG. 3 is a plan view of a second side of the long segment of the wristband for an electronic device.

FIG. 4 is a first end view of the long segment of the wristband for an electronic device.

FIG. 5 is a second end view of the long segment of the wristband for an electronic device.

FIG. 6 is a first perspective view of the long segment of the wristband for an electronic device.

FIG. 7 is a second perspective view of the long segment of the wristband for an electronic device.

FIG. 8 is a plan view of a first side of a short segment of the wristband for an electronic device.

FIG. 9 is an edge view of the short segment of the wristband for an electronic device.

FIG. 10 is a plan view of a second side of the short segment of the wristband for an electronic device.

FIG. 11 is a first end view of the short segment of the wristband for an electronic device.

FIG. 12 is a second end view of the short segment of the wristband for an electronic device.

FIG. 13 is a plan view of a first side of the long segment coupled to the short segment of the wristband for an electronic device.

FIG. 14 is an edge view of the long segment coupled to the short segment of the wristband for an electronic device.

FIG. 15 is a plan view of a second side of the long segment coupled to the short segment of the wristband for an electronic device.

FIG. 16 is a first end view of the long segment coupled to the short segment of the wristband for an electronic device.

FIG. 17 is a second end view of the long segment coupled to the short segment of the wristband for an electronic device.

(Continued)

FIG. 18 is a first perspective view of the long segment coupled to the short segment of the wristband for an electronic device; and,

FIG. 19 is a second perspective view of the long segment coupled to the short segment of the wristband for an electronic device.

The broken lines shown in the drawings illustrate end portions of the wristband for an electronic device and form no part of the claimed design.
